DETACHABLE TERMINAL FITTING FOR
STRANDED-WIRE STRUCTURE

Alan E. Brickman, New Haven, Conn., assignor to
The American Steel and Wire Company of New
Jersey, a corporation of New Jersey

Application February 2, 1943, Serial No. 474,416

6 Claims. (Cl. 24—122.6)

1

This invention relates to a detachable terminal fitting, and in particular to such fittings used on stranded wire structures. At present all terminals are fixed to the end of the stranded wire structure so as to become a unitary part of the assembly. If the terminal becomes worn or damaged, the whole assembly must be replaced. All apertures through which the cable passes must be equal to or greater than the largest cross-section of the attached terminal. These large apertures weaken the structure and/or permit undesirable infiltration of moisture, gases or foreign materials and are especially detrimental when used on aeroplanes.

In the present fixed terminals there is no immediate provision for changing the overall length of the cable assembly. Such change is often necessary due to lengthening resulting from structural stretch of the cable or from wear, which is particularly noticeable in cable connections involving marked changes in course of direction, as accomplished with sheaves. The present used cable connector with fixed terminals must, therefore, include a turnbuckle or a stud fitting with nut takeup on at least one end to compensate for the changes in cable assembly length.

It is an object of this invention to furnish a detachable terminal fitting which permits greater flexibility of terminal design.

Another object is to furnish a terminal fitting which may be readily removed or replaced.

A further object is to furnish a terminal fitting having provisions for changing the overall length of the cable assembly.

These and other objects will be more apparent after referring to the attached drawings in which:

Fig. 1 is a view of a stranded wire structure used in the invention;

Fig. 2 is a view of such a wire structure after its end has been broomed;

Fig. 3 is a view, partly in cross-section, showing a fitting attached to the stranded wire structure;

Fig. 4 is a view of the terminal fitting of the invention;

Fig. 5 shows the fitting assembly;

Fig. 6 is an enlarged sectional view of a detail of the invention;

Fig. 7 is a view similar to Fig. 6 showing the parts in a different position;

Fig. 8 is a view of a fitting used in a second embodiment of the invention;

Fig. 9 is an end view of the fitting of Fig. 8;

Fig. 10 shows the fitting of Fig. 8 swaged on the wire rope;

2

Fig. 11 is a view similar to Fig. 10, but showing the fitting with the threads formed thereon, and

Fig. 12 is a view showing an assembly of the second embodiment of the invention.

Referring more particularly to the drawings, reference numeral 2 indicates a stranded wire structure to which a fitting is to be attached. The wire structure is broomed to obtain a bulb 4 a short distance from the end thereof and an enlarged broomed section 6 at the end thereof as shown in Fig. 2. The end of the wire structure is then inserted into the cavity of a die and molten metal is injected into the cavity of the die to produce a fitting 8 bonded to the stranded wire structure as shown in Fig. 3. The fitting has threads 10 cast thereon which are cleaned and finished by running a Dardelet thread die thereover.

A detachable terminal fitting 14 having a bore 16 formed therein is produced by the injection method of die casting. A Dardelet thread 18 is cast therein and a thread tap is run over the cast thread to clean and finish the working surfaces. A set screw 20 is then screwed into the bottom of the bore 16. By adjusting this screw the bottoming point may be changed as desired.

The operation of the Dardelet thread will be apparent from an inspection of Figs. 6 and 7. The root portion 22 of the male thread is tapered 30 so as to cause an incline in the direction of the end and there is a corresponding taper 24 on the crest portion of the female thread. The two members may be readily screwed together until they meet with resistance, which in this instance takes place when the fitting 8 abuts the plug 20.

With the addition of torque, the crest taper produces a great compressive force on the root taper of the cable member, which, in turn, will transmit the compression forces onto the stranded wire structure to increase the grip on the stranded 35 structure to better withstand the tension which will be applied to the assembly. Fig. 7 shows the position of the thread when additional torque is applied. To provide changes in the overall assembly length, the plug 20 may be adjusted inwardly or outwardly by means of a set screw wrench 26.

A second embodiment of the invention is disclosed in Figs. 8 to 12. In this embodiment a tubular nickel steel seamless ferrule 27 provided with a bore 28 having a diameter comparative to the outside diameter of the wire structure is slid over the wire. The ferrule is then swaged over the greater part of its length so as 40 to cause flow of metal into the external inter-

55 stices and in fist grip with the stranded wire

structure as shown in Fig. 10. The finished wall section on the ferrule in this construction may be extremely thin, as it becomes augmented with the values produced by the detachable terminal 14 as described above. The unswaged length 29 of the ferrule fits closely about the stranded wire and functions as a vibration dampener. In the usual terminal fittings of the swaged assembly type there is a taper of 12 degrees inside and out or 24 degrees outside for a short distance back from the end of the cable hole so that there will be a progressive diminishing of grip on the wire structure. This method of evading a line of restraint to cable vibration is not as effective as the method disclosed above. After the ferrule 21 is swaged onto the wire, a Dardelet thread 30 is cut on the swaged portion and the terminal fitting 14 is then screwed on the ferrule 21. It will be apparent that any type of terminal fitting may be substituted for the one shown.

While two embodiments of the invention have been shown and described, it will be apparent to one skilled in the art that other embodiments and adaptations may be made without departing from the scope of the attached claims.

I claim:

1. A terminal fitting for stranded wire structures comprising a thin walled compressible fitting surrounding and in intimate surface contact with said stranded wire structure and having a Dardelet thread formed on the external surface thereof, and a hollow fitting having a complemental Dardelet thread formed on the internal surface thereof and threaded on said first-named fitting, said complemental threads being tightened to compress the compressible fitting whereby the gripping force on the wire structures is increased.

2. A terminal fitting for stranded wire structures comprising a thin walled compressible fitting surrounding and in intimate surface contact with said stranded wire structure and having a Dardelet thread formed on the external surface thereof, and a hollow fitting having a complemental Dardelet thread formed on the internal surface thereof and threaded on said first-named fitting, said complemental threads being tightened to compress the compressible fitting whereby the gripping force on the wire structures is increased, said hollow fitting having an adjustable bottom therein to provide changes in the assembled length of the terminal fitting.

3. A terminal fitting for stranded wire structures comprising a thin walled compressible male fitting cast about said stranded wire structure, and having a Dardelet thread formed on the external surface thereof, and a hollow fitting having a complemental Dardelet thread formed on the internal surface thereof and threaded on said first-named fitting, said complemental threads being tightened to compress the compressible fitting whereby the gripping force on the wire structures is increased.

4. A terminal fitting for stranded wire structures comprising a thin walled compressible male fitting cast about said stranded wire structure, and having a Dardelet thread formed on the external surface thereof, and a hollow fitting having a complemental Dardelet thread formed on the internal surface thereof and threaded on said first-named fitting, said complemental threads being tightened to compress the compressible fitting whereby the gripping force on the wire structures is increased, said hollow fitting having an adjustable bottom therein to provide changes in the assembled length of the terminal fitting.

5. A terminal fitting for stranded wire structures comprising a thin walled compressible male fitting swaged to and surrounding the wire structure and having a Dardelet thread formed on the external surface thereof, and a hollow fitting having a complemental Dardelet thread formed on the internal surface thereof and threaded on said first-named fitting, said complemental threads being tightened to compress the compressible fitting whereby the gripping force on the wire structures is increased.

6. A terminal fitting for stranded wire structures comprising a thin walled compressible male fitting swaged to and surrounding the wire structure and having a Dardelet thread formed on the external surface thereof, and a hollow fitting having a complemental Dardelet thread formed on the internal surface thereof, and threaded on said first-named fitting, said complemental threads being tightened to compress the compressible fitting whereby the gripping force on the wire structures is increased, said hollow fitting having an adjustable bottom therein to provide changes in the assembled length of the terminal fitting.

ALAN E. BRICKMAN.
